RAYMOND T. PIERCE, OF EAST PITTSBURGH, PENNSYLVANIA, ASSIGNOR TO WESTINGHOUSE ELECTRIC & MANUFACTURING COMPANY, A CORPORATION OF PENNSYLVANIA.

ELECTRICAL MEASURING INSTRUMENT.

Application filed May 12, 1923. Serial No. 638,626.

My invention relates to electrical measuring instruments and particularly to alternating-current ammeter or voltmeter mechanisms.

- 5 One object of my invention is to provide a device of the above-indicated character that shall be simple and durable in construction, economical to manufacture and effective in its operation.
- 10 Another object of my invention is to provide an alternating-current instrument that shall be better balanced, that shall have smoother operating characteristics and that shall operate over a more uniform scale.

- 15 Another object of my invention is to provide an ammeter structure that shall be very easy to assemble and that shall not readily get out of order.

- 20 A further object of my invention is to provide an ammeter structure that shall be extremely compact and neat in appearance.

In practicing my invention, I provide a stationary hollow coil, a shaft disposed in spaced parallel-plane relation thereto and an 25 armature disc mounted eccentrically on the shaft to be attracted by uniform increments into the space encompassed by the coil. The various details of construction combine to render the arrangement extremely effective 30 in operation, to simplify the assembly, to provide a uniform scale movement and to economize to a marked degree in the production of a high-grade instrument.

Figure 1 of the accompanying drawing is 35 a plan view of a portion of an instrument embodying my invention.

Fig. 2 is a side elevational view of the instrument shown in Fig. 1.

Fig. 3 is a detail plan view of a novel 40 form of armature disk employed in my invention.

The device of my invention comprises, in general, a stationary coil 1, a shaft 2, an armature disk 3, a bushing 4, a balance-weight 45 arm 5 and a balance weight 6.

The coil 1, having conducting leads 8 and 9, is preferably of substantially oval shape to provide an elongated narrow opening 10 therein.

50 The shaft 2, having usual end bearing portions 11 and 12, is disposed in spaced parallel-plane relation to the coil 1 and is adapted to receive the disc 3 at a position opposite the opening 10 in the coil 1.

The disc 3 is preferably of uniform circular shape, except for a notch 14 in the periphery thereof, although it may be otherwise formed, and is provided with an opening 15 that is offset from the central axis 55 thereof.

The bushing 4, that is preferably press-fitted in position on the shaft 2 opposite the opening 10 in the coil 1, has cylindrical portions 16 and 17 of different diameter to provide a shoulder 18 against which the disk 3 60 rests, when the smaller diameter portion 16 is in position in the opening 15 of the disk.

The balance-weight arm 5 comprises a flat discoidal inner portion 19, having an opening by which it also surrounds the smaller portion 16 of the bushing 4, and a radially projecting arm portion that is bent laterally 65 through the notch 14.

After the above described members have 70 been assembled in the positions shown, the upper end 21 of the bushing 4 is swaged over to securely hold the disk 3 and the balance-weight arm 5 in position on the bushing 4. The arrangement by which the balance-weight arm 5 is swaged in position at its 75 inner end and is positioned in the notch 14 provides an extremely simple and effective 80 method of fixing the arm 5 in position relative to the disk 3.

In operation, the disk 3 being eccentrically mounted on the shaft 2, will be drawn into the opening 10 by uniformly varying degrees in proportion to the current traversing the coil 1 in opposition to a usual spring 90 (not shown) that is connected to the shaft 2. The degree of eccentricity of the disk 3 relative to the shaft 2 is predetermined to cause the latter to run through substantially equal increments of angular movement in response 95 to equal increases of current in the coil 1, thereby permitting the use of a more uniform scale and greatly improving the operation of the instrument.

While I have shown and described a particular form of my invention, changes may be effected therein without departing from the spirit and scope thereof, as set forth in the appended claims.

I claim as my invention:

1. In an electrical measuring instrument, 105 the combination with a shaft, of an armature disk member mounted thereon, and a

balance-weight arm member secured to said shaft and extending laterally therefrom, one of said members having means co-operating with the other at a position removed from 5 the shaft for preventing angular movement of the arm relative to the disk.

2. In an electrical measuring instrument, the combination with a shaft, of an armature disk member mounted thereon, and a 10 balance-weight arm member secured to said shaft and extending laterally therefrom, one of said members having means co-operating with the other at the periphery of the disk to prevent angular movement of the arm 15 relative to the disk.

3. In an electrical measuring instrument, the combination with a shaft, of an armature disk mounted theron and having a peripheral notch, and a balance-weight arm 20 secured to said shaft and extending along a surface of the disk and laterally through said notch to prevent angular movement of the arm relative to the disk.

4. In an electrical measuring instrument, 25 the combination with a shaft, of an armature disk mounted eccentrically thereon and having a peripheral notch at the end of the shortest distance from the shaft on the diameter of the disk through the axis of the 30 shaft, and a balance-weight arm secured to said shaft and extending along a surface of the disk and laterally through said notch to prevent angular displacement of the arm relative to the disk.

35 5. In an electrical measuring instrument, the combination with a coil and a shaft, of an armature disk member having an opening therethrough, a balance-weight arm having an opening registering with said disk opening and a portion extending laterally from the shaft, a bushing on the shaft having portions of different diameters to provide a shoulder against which said members rest, the smaller portion of the bushing 40 extending through said openings and being provided with means to hold the disk and the arm in position, and means cooperating between the arm and the disk at a position removed from the shaft for preventing angular 45 movement of the arm relative to the disk.

6. In an electrical measuring instrument, the combination with a coil and a shaft, of 50 an armature disk member having an opening therethrough and a peripheral notch, a balance-weight arm having an opening registering with said disk opening and a portion extending laterally from the shaft and longitudinally through said notch, and 55 means for holding the disk and the arm in position comprising a bushing on the shaft having portions of different diameters to provide a shoulder against which said members rest, the smaller portion of the bushing 60 extending through said openings.

7. In an electrical measuring instrument, the combination with a coil and a shaft, of 65 an armature disk member having an opening therethrough offset from the center thereof and a peripheral notch at the end of the shorter distance from the opening on the diameter of the disk through the opening, a balance-weight arm having an opening 70 registering with said disk opening and a portion extending therefrom along a surface of the disk, through said notch and outwardly from the edge of the disk, a bushing on the shaft having portions of different diameters to provide a shoulder against which 75 said members rest the smaller portion of the bushing extending through said openings and being swaged over to hold the disk and the arm in position, and a balance-weight member on said outwardly-extending portion of the arm.

8. In an electrical measuring instrument, the combination with a coil, of a plurality 80 of members comprising a shaft and an armature disk of magnetizable material, said armature disk being carried by said shaft, having its weight non-uniformly disposed with respect to the axis of said shaft and projecting into the space encompassed by said coil, an arm carried by one of said members, and a weight adjustable on said arm outwardly of the periphery of said armature disk, said weight being disposed substantially in the plane of said disk and on the side of said shaft occupied by the disk-portion of minor weight.

9. In an electrical measuring instrument, the combination with a coil, of a plurality 85 of members comprising a shaft and an armature disk of magnetizable material, said armature disk being eccentrically mounted 90 on said shaft, having its weight non-uniformly disposed with respect to the axis of said shaft and projecting into the space encompassed by said coil, and a counterbalancing weight carried by one of said members, said counterbalancing weight being disposed substantially in the plane of said disk and on the side of said shaft occupied by the disk-portion of minor weight.

10. In an electrical measuring instrument, 100 the combination with a coil, of a plurality of members comprising a shaft and an armature disk of magnetizable material, said armature disk being eccentrically mounted on 105 said shaft, having its weight non-uniformly disposed with respect to the axis of said shaft and projecting into the space encompassed by said coil, and a counterbalancing weight connected to said armature disk independently of said shaft and disposed on 110 the side thereof occupied by the disk-portion of minor weight.

11. In an electrical measuring instrument, the combination with a coil, of a plurality 115 of members comprising a shaft and an ar-

mature disk of magnetizable material, said armature disk being eccentrically mounted on said shaft, having its weight non-uniformly disposed with respect to the axis of said shaft and projecting into the space encompassed by said coil, and a counterbalancing weight carried by one of said members substantially in the plane of said disk, a line

passing through the center of gravity of said disk and counterbalancing weight substantially coinciding with the axis of said shaft. ¹⁰

In testimony whereof, I have hereunto subscribed my name this 9th day of May, 1923.

RAYMOND T. PIERCE.
